UNITED STATES PATENT OFFICE.

JOHN ALLEN HEANY, OF PHILADELPHIA, PENNSYLVANIA, ASSIGNOR TO THE TETER-HEANY DEVELOPING COMPANY, OF CHARLESTON, WEST VIRGINIA, AND PHILADELPHIA, PENNSYLVANIA, A CORPORATION OF WEST VIRGINIA.

ELECTRIC-ARC LAMP.

SPECIFICATION forming part of Letters Patent No. 740,132, dated September 29, 1903.

Application filed January 7, 1903. Serial No. 138,108. (No model.)

To all whom it may concern:

Be it known that I, JOHN ALLEN HEANY, a citizen of the United States, residing at the city of Philadelphia, in the county of Philadelphia and State of Pennsylvania, have invented certain new and useful Improvements in Electric-Arc Lamps, of which the following is a specification.

My invention has relation to that class of arc-lamps in which the arc is preferably maintained within a small and practically-sealed globe; and in such connection it relates to the construction and arrangement of the parts constituting such an arc-lamp.

15 The nature and scope of my invention will be more fully understood from the following description, taken in connection with the accompanying drawings, forming part hereof, in which—

20 Figure 1 is a view, partly in section and partly in front elevation, of an electric-arc lamp embodying main features of my invention. Fig. 2 is a vertical sectional view taken at a right angle to Fig. 1. Fig. 3 is a horizontal sectional view, enlarged, illustrating in top plan view the base of the arc-lamp. Fig. 4 is a horizontal sectional view, enlarged, 25 illustrating in top plan view a base-plate adapted to support the inner globe and a holder for the outer globe. Fig. 5 is a horizontal sectional view, enlarged, taken on the line $x-x$ of Fig. 2; and Fig. 6 is a detail view, enlarged, illustrating in top plan view a bracket for the solenoid-coil, which may be 30 readily connected to and disconnected from the framework of the lamp.

Referring to the drawings, A represents the base, consisting of a centrally-contracted or body portion a , from which extend upwardly and downwardly projecting flanges a' and a'' . The central body portion a and flanges a' and a'' of the base-plate A may either consist of a double casting, as shown, or of a single casting or stamped-up device. To the lower flange a'' of the base A by means of screws a^3 is secured a base-plate b , which is held a certain distance from the base A by sleeves a^4 , surrounding the screws a^3 , as shown in Fig. 2. Against the lower face of the base-plate b 45 by means not shown is held the inner globe c , which is adapted to receive the lower carbon d and a portion of the upper carbon d' and in which the arc in the well-known manner is maintained. The lower carbon d is held in position within the globe c by means 55 of a holder d^2 , properly secured to and insulated from the base-plate b , and the upper carbon d' is preferably conducted through an insulating-sleeve d^3 , which is secured in the base-plate b . The upper face of the base-plate b serves as a support for a clutch e , which engages the upper carbon d' and is provided with an insulating-disk b' , preferably of mica, to properly insulate the clutch e from the base-plate b . The supporting-screws a^3 65 for the base-plate b engage, preferably, radially-projecting arms or lugs b^2 of the same, which also serve as a support for a globe-holder f , as shown in Figs. 2 and 4. The globe-holder f by means of screws f^2 is removably secured 70 to the lugs b^2 and is provided with a downwardly-projecting flange f' , which fits over the upper open end of the outer globe g and supports the same by means of screws f^3 . Between the lugs b^2 of the base-plate b and the 75 globe-holder f are formed openings g' , which permit the air heated in the space g^2 between the inner and outer globes c and g to readily escape into the outer atmospherical air by passing through an annular opening g^3 , arranged 80 between the globe-holder f and the vertical-projecting rim a^5 of the flange a^2 of the base A. By loosening the screws f^3 the outer globe g may be readily disconnected from the globe-holder f and the inner globe c made accessible 85 for the removal and insertion of the carbons d and d' . The upper flange a' of the base A is provided with vertically-projecting rods a^6 , normally engaging the tubes h , secured to a frame h' . The frame h' is provided with a tubular extension h^2 , forming a seat for the upper end of a tube i , surrounding and guiding the upper carbon d' , which tube i loosely engages an insulating-washer h^3 , located in the end of the tubular extension h^2 of the frame h' , so as to properly insulate the same from the said frame h' . The lower threaded end of the tube i is screwed 95 into an insulating-sleeve a^7 , arranged in the body portion a of the base A, and is securely 100

clamped thereto by means of a plate i' and a nut i^2 , insulated from the portion a . The threaded contracted portion h^4 of the extension h^2 carries a cap k , which by means of 5 bolts or screws k^2 supports a casing or housing k' , inclosing the upper portion of the lamp in such a manner as that air entering the lower open end of the casing k' may readily escape at the upper end through an annular 10 opening k^3 , arranged between the downwardly-projecting rim of the cap k and the casing or housing k' . To the threaded portion h^4 of the extension h^2 of the frame h' is secured in the usual manner a hook or ring, 15 (not shown,) by means of which the lamp may be suspended from the ceiling of a building or from any other suitable support. The frame h' , with its extensions h^2 and h^4 and tubes h , forms, in conjunction with the rods a^6 , the tube 20 i , and the flange a' of the base A , the framework B of the lamp. This framework is securely connected to the base A by means of connecting-screws h^5 , passing through the tubes h , and the rods a^6 , loosely mounted 25 therein, as shown in Figs. 2 and 3. Within the tube i is slidably arranged a cap or holder i^3 , adapted to receive in its interior the upper end of the movable carbon d' . The holder i^3 is provided with a binding-post i^4 , passing 30 through a slot i^5 , arranged in the tube i , to which post a wire 1 is secured, which conducts the electric current into the holder i^3 and carbons d' and d and through the holder i^3 to a wire 2, from which the same may pass in an 35 opposite direction to the wire 1, and so close the circuit through the carbons. In order to utilize the whole length of the tube i for the reception of the upper carbon d' , the tubular extension h^2 of the frame h' is provided with a 40 slot h^6 , which permits the holder i^3 of the carbon d' to rise to the upper end of the tube i and in this manner to permit of the use of a carbon of an exceptional length in respect to size of the lamp. The clutch e , engaging the 45 carbon d' , is actuated by a rod e' , passing through an opening a^9 , arranged in the body portion a of the base A , and through a plate i' serves as a clamping-nut for the tube i and ending in a guide i^6 , composed, preferably, 50 of insulating material partially surrounding the tube i and slidably arranged thereon. The clutch-rod e' preferably passes loosely through a solenoid-core l , the arms l' and l^2 of which engage the solenoid-coils m and m' , 55 which when energized by an electric current draw the arms l' and l^2 into the same and in such a well-known manner actuates the rod e' and clutch e and raises the upper carbon d from the lower carbon to form the electric 60 arc between the same. In order to check the rapid upward movement of the core l , clutch e , and carbon d' , to the rod e' is adjustably clamped an arm e^2 , engaging a dash-pot n of well-known construction, which in conjunction 65 with the springs e^3 and e^4 , arranged between the arm e^2 and core l and between the same and a plate e^5 , secured to the rod e , retards

a rapid upward movement. As shown in Figs. 2 and 3, the contracted lower end n' of the dash-pot n is engaged by a clamp n^2 , which 70 surrounds a stud a^8 of the base A , into which one of the rods a^6 is secured. The clamp n^2 by means of an insulating-ring n^3 is insulated 75 from the stud a^8 and can be readily clamped thereon, as well as to the dash-pot n , by a bolt n^4 , passing through the clamp n^2 , which by means of a nut n^5 draws the central portion 80 of the clamp n^2 together. By loosening the nut n^5 the end n' of the dash-pot n may be readily disengaged from the clamp n^2 . 85

By the above-described arrangement and construction of the framework B of the lamp the lower portion and globes c and g , base A , as well as the tube i for the upper carbon d' , the solenoid-core l , clutch-rod e' , clutch e , 90 dash-pot n , and rods a^6 may be readily disconnected from the frame h' and its tubes h by disengaging the screws h^5 from the tubes h and the rods a^6 for repairs or cleaning of the working parts of the lamp, as shown in dotted lines in Fig. 2. At the same time the lamp may be readily assembled, in which instance the rods a^6 are shifted back into the tubes h and the carbon-tube i into the extension h^2 of the frame h' . In order to also permit the ready disengagement of the solenoid-coils m and m' from their supporting-tube h , the coils at their upper and lower ends are provided with brackets m^2 , having a loop-like extension m^3 , surrounding the tube h in 100 a semicircular form. Each of the brackets m^2 is securely clamped to the supporting-tube h by means of a screw m^4 , provided with a conical-shaped end m^5 , which engages the tube h , as shown in Fig. 6, and which by advancing on the tube h produces the necessary 105 friction to hold the solenoid-coils in any given position. At the same time these clamping-screws m^5 , in conjunction with the brackets m^2 , form the means of readily disengaging the solenoid-coils m and m' from the framework B of the lamp. 110

The frame h' of the framework B of the lamp, with its extension h^2 , affords a ready 115 means of support of either a resistance-coil or a choke-coil, so that the lamp, as described and shown, may be used either as a direct-current lamp or as an alternating-current lamp.

Having thus described the nature and objects of my invention, what I claim as new, and desire to secure by Letters Patent, is—

1. In an electric-arc lamp, a base having dome-shaped upper and lower flanges, a base-plate suspended from the lower dome-shaped 125 flange, an outer and an inner globe carried by said plate, a series of rods carried by the upper dome-shaped flange, a carbon-tube centrally secured at its lower end in said base intermediate of said flanges, a frame adapted 130 to detachably engage the upper end of said carbon-tube, and a series of tubes carried by said frame and adapted to detachably engage the rods of said upper dome-shaped flange. 135

2. In an electric-arc lamp, a base having an upwardly and a downwardly projecting flange, a base-plate suspended from the downwardly-projecting flange, an inner and an outer globe carried by said base-plate, a series of rods carried by the upwardly-projecting flange, a carbon-tube secured at its lower end in said base, a frame having an extension adapted to engage the upper end of said carbon-tube, a series of tubes carried by said frame and adapted to loosely engage the series of rods of the upwardly-projecting flange, said flange, rods, tubes, frame and carbon-tube constituting the upper framework of the lamp.
3. In an electric-arc lamp, a base having an upwardly and a downwardly projecting flange, a series of rods projecting from the upwardly-projecting flange, a frame, a series of tubes suspended from said frame and engaging said rods, and means adapted to detachably connect said tubes with said rods.
4. In an electric-arc lamp, a base having an upwardly and a downwardly projecting dome-shaped flange, a series of rods projecting from the upwardly-projecting dome-shaped flange, a carbon-tube secured in said base intermediate of said flanges, and a dash-pot detachably secured to the upwardly-projecting dome-shaped flange of said base.
5. In an electric-arc lamp, a base having an upwardly and a downwardly projecting flange, a series of rods projecting from the upwardly-projecting flange, a carbon-tube centrally secured in the body portion of said base, a dash-pot, means for detachably connecting said dash-pot with the upwardly-projecting flange, a frame adapted to detachably engage said carbon-tube, a series of tubes secured to said frame and adapted to detachably engage said rods, a solenoid-coil, and means adapted to adjustably and detachably connect said coil with one of said tubes.
6. In an electric-arc lamp, a base having flanges upwardly and downwardly projecting therefrom, a base-plate suspended from the lower one of said flanges and adapted to support an outer and an inner globe, a series of tubes projecting from the upper one of said flanges, a carbon-tube arranged centrally in said base, a frame having a series of tubes, said frame adapted to detachably engage said carbon-tube and said tubes adapted to detachably engage said rods.
7. In an electric-arc lamp, a base having flanges upwardly and downwardly projecting therefrom, a base-plate suspended from the lower one of said flanges and adapted to support an outer and an inner globe, a series of tubes upwardly projecting from the upper one of said flanges, a carbon-tube centrally arranged in said base, a frame having a series of tubes suspended therefrom, said frame adapted to engage said carbon-tube and said tubes adapted to engage said series of rods, a clutch-rod, a clutch actuated by said rod, a solenoid-core, and a dash-pot, said base-plate, globes, rods, carbon-tube, clutch-rod, solenoid-core and dash-pot so arranged as to be readily detachable from said frame and its tubes.
8. In an electric-arc lamp, a base having flanges, upwardly and downwardly projecting therefrom, a base-plate carried by the lower one of said flanges, an inner globe adapted to be carried by said base-plate, a globe-holder and outer globe adapted to be supported by said base-plate so as to form air-outlets between the base-plate, outer globe, globe-holder and the lower of said flanges, rods carried by the upper one of said flanges, a frame having tubes engaging said rods, a cap adapted to be supported by said frame, a housing projecting below the upper one of said flanges and connected with said cap so as to form an air-outlet between said cap and housing.
9. In an electric-arc lamp, having a base, a slotted carbon-tube arranged in said base, a frame having a slotted extension engaging said carbon-tube, a carbon-holder arranged within said carbon-tube and movable therein, and a binding-post connected with said carbon-holder and passing through the slot of said carbon-tube and adapted to be afforded a range of movement in said slot and within the extension of said frame.
10. In an electric-arc lamp, a base, a series of rods projecting from said base, a frame having a series of tubes adapted to engage said rods, a solenoid-coil, brackets connected with said coil having a loop-like extension adapted to detachably engage one of said tubes, and means adapted to clamp said brackets to said supporting-tube.
- In testimony whereof I have hereunto set my signature in the presence of two subscribing witnesses.
